(57) **CLAIM**

The ornamental design for a motorcycle footrest, as shown and described.

DESCRIPTION

FIG. 1 is a perspective view of a first embodiment of the motorcycle footrest;

FIG. 2 is a left side elevation view of the embodiment of FIG. 1;

FIG. 3 is a right side elevation view of the embodiment of FIG. 1;

FIG. 4 is a front elevation view of the embodiment of FIG. 1;

FIG. 5 is a rear elevation view of the embodiment of FIG. 1;

FIG. 6 is a top plan view of the embodiment of FIG. 1; and, FIG. 7 is a bottom plan view of the embodiment of FIG. 1. The broken lines shown illustrate portions of the motorcycle footrest that form no part of the claimed design.

1 Claim, 5 Drawing Sheets(56)
